(57) **CLAIM**

The ornamental design for a board with stand, as shown and described.

DESCRIPTION

FIG. 1 is a first perspective view of a board with stand showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is another perspective view of an alternate state of the board with stand thereof;

FIG. 10 is another perspective view of an alternate state of the board with stand thereof; and,

FIG. 11 is another perspective view of an alternate state of the board with stand thereof.

The broken lines shown in the drawings depict portions of the board with stand in which the design is embodied that form no part of the claimed design.
